CLAIM

What is claimed is the ornamental design for a lamp, as shown and described.

DESCRIPTION

FIG. 1 is a top, front perspective view of the lamp showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view of thereof;

FIG. 8 is a rear, bottom perspective view of the lamp, showing the light bar rotated to an alternate position; and, FIG. 9 is a top, front perspective view of the lamp showing the light bar rotated to another alternate position.

The lamp is shown with symbolic breaks in its length. The appearance of any portion of the article between the hash marks on the light bar, and the broken lines on the rectangular mount form no part of the claimed design. The portions of the lamp shown in broken lines indicate breaks in the length of those portions, and form no part of the claimed design.
